UNITED STATES PATENT OFFICE.

JEROME B. KESTER, OF CLARKSBURG, WEST VIRGINIA.

SASH-FASTENER.

SPECIFICATION forming part of Letters Patent No. 377,522, dated February 7, 1888.

Application filed September 9, 1887. Serial No. 249,254. (No model.)

To all whom it may concern:

Be it known that I, JEROME BONAPARTE KESTER, of Clarksburg, in the county of Harrison and State of West Virginia, have invented a new and Improved Window-Sash Fastening, of which the following is a full, clear, and exact description.

My invention relates to fastenings for locking upper and lower sashes closed or open to any desired extent in the window-frame; and the invention has for its object to provide a simple, inexpensive, and effective device of this character.

The invention consists in certain novel features of construction of the sash-fastening, all as hereinafter described and claimed.

Reference is to be had to the accompanying drawings, forming a part of this specification, in which similar letters of reference indicate corresponding parts in all the figures.

Figure 1 is an inside face view of a window-frame and upper and lower sashes therein with my improved fastenings applied to the sashes and with the window-frame partly broken away and in section. Fig. 2 is a vertical sectional side view thereof, taken on the line *xx*, Fig. 1. Fig. 3 is a plan view in section on the line *yy*, Fig. 1; and Fig. 4 is a detail plan view taken on the line *zz*, Fig. 1.

The window-frame *A* and upper and lower sashes, *B C*, may have any approved construction. The frame is shown with the ordinary stop-bead, *D*, at the inside of the lower sash and with the usual parting-strip, *E*, between the sashes.

The fastenings for both the lower and upper sashes embody the same principles of construction, but differ somewhat in form to adapt them to their respective sashes, as I will hereinafter explain. I will more particularly describe the invention with reference first to the fastening on the lower sash, and as follows:

In its preferred form the sash-fastening consists of three main parts—a metal plate, *F*, which is attached by screws or otherwise to the inner face of the sash, a metal latch-bar, *G*, pivoted at *g* to the plate *F*, and a metal lock-bar, *H*, pivoted at *h* to the plate *F*. The latch *G* has a right-angular general form, and its short arm *g'* is adapted to enter any one of a series of notches, *I*, made in the adjacent

stop-bead *D*, and the long arm *g'* of the latch is provided at its free end with a shoulder, *g''*, onto which the free end *h'* of the lock *H* rests or overlaps when the parts are in normal positions. A stop-pin, *J*, in the plate *F* limits the swinging movement of the latch *G* toward the side of the window-frame. 55

To the lock *H* is fixed one end of a wire bridge or staple, *K*, which passes over the face 60 of the latch *G*, and at its extremity is bent inward to form a catch or pull, *k*, which normally stands off sufficiently from the latch *G* to allow the lock *H* to be swung sidewise by pressing its knob *h''* until the end *h'* of the 65 lock clears the shoulder *g''* of the latch, whereupon the catch *k* will, by contact with the latch *G*, swing it away from the frame *A* and withdraw its arm *g'* from the notch *I* of the window-frame, as indicated in dotted lines in Fig. 1 of 70 the drawings, and the sash may then be slid up or down freely; but when the lock *H* is let go or released from the hand the parts *G H* will swing downward by gravity, and as the latch *G* strikes the stop *J* and enters a notch 75 *I* the lock *H* will swing in over the shoulder *g''* of the latch *G*, and will lock it into the notch *I* of the window-frame until the lock *H* is again swung sidewise clear of the latch-shoulder *g''*, as will readily be understood. 80

The fastening for the upper sash is like the lower one, except that the arm *g'* of the latch is at the lower end of it instead of at the upper end, and the operation of the upper-sash fastening is precisely similar to that of the lower-sash fastening, except that the latch-arm *g'* enters a notch *I* made in the parting-strip *E* instead of the stop-bead *D*. The knob or button *h''* of the lock *H* of the upper fastening is made short or flat to allow the lower sash to 90 pass over it or allow it to pass behind the lower sash as the sashes are moved in the window-frame.

The main plate *F* is not essential to the successful operation of my invention, as the parts 95 *G H*, or *G, H*, and *K*, which are its principal features, would operate successfully were they connected directly to the faces of the sashes; but the advantages of the plate *F* are so obvious in allowing proper adjustment of the parts and 100 easy connection of them to the sashes that the main plate cannot well be dispensed with.

Having thus described my invention, what I claim as new, and desire to secure by Letters Patent, is—

1. A window-sash fastening comprising a gravitating latch pivoted to the sash and adapted to a notch or detent at the window-frame and provided at its pendent part with a shoulder, a gravitating lock pivoted to the window-sash and adapted to overlie the latch-shoulder, and a bridge or catch on the lock allowing it to be withdrawn from the latch-shoulder before acting on the latch to disengage it from the window-frame, substantially as herein set forth.
- 15 2. The combination, in a sash-fastening, of a plate, F, a gravitating latch, G, pivoted thereto and having an arm, g' , adapted to a notch or detent at the window-frame, and provided also with a shoulder, g^3 , a lock, H, pivoted to the plate F and adapted to the latch-shoulder

g^3 , and a bridge, K, having a catch, k , allowing the lock to be disengaged from the latch-shoulder before disengaging the latch from the window-frame, substantially as herein set forth.

3. In a window-sash fastening, the combination of a gravitating latch, G, pivoted to the sash and provided with an arm, g' , and a shoulder, g^3 , a lock, H, pivoted to the sash and adapted to the latch-shoulder g^3 , a bridge, K, held to the lock and having a catch, k , allowing the lock to be disengaged from the latch-shoulder before disengaging the latch from the window-frame, and a stop, J, limiting the movements of the latch and lock, substantially as herein set forth.

JEROME B. KESTER.
